UNITED STATES PATENT OFFICE.

EUGENE CONTI, OF CLIFFSIDE PARK, NEW JERSEY, ASSIGNOR TO ALEXANDER HERZ,
OF NEW ROCHELLE, NEW YORK.

CUTTING MACHINE.

Application filed June 3, 1922. Serial No. 565,646.

To all whom it may concern:

Be it known that I, EUGENE CONTI, a citizen of the United States, and a resident of Cliffside Park, Bergen County, New Jersey, have invented an Improvement in Cutting Machines, of which the following is a specification.

My invention relates to cutting machines and the object thereof is to produce a machine of this type which is of improved construction and cuts the material in an improved and more satisfactory manner. Inasmuch as my machine is of particular utility in the manufacture of paper tubes I have chosen, for purpose of illustration, a machine designed for cutting such tubes. In the drawings accompanying this specification and forming a part thereof:

Figure 1 is a side elevation of this illustrative embodiment of my invention;

Figure 2 is an end elevation of the machine shown in Figure 1;

Figure 3 is a plan of this machine; while

Figure 4 represents a detail view of certain portions of this machine.

Many of the tube forming machines in use at the present time produce a tube which is continuously fed from the machine in one continuous tube of great length and must thereafter be severed into the desired short sections. The machine which I have herein illustrated is provided for this purpose and in operation may be secured to and made a part of the general tube forming machine. I have omitted, however, all illustration of any tube forming machine and have merely shown the tube 11 as it is being fed forward from the forming machine.

Mechanism is necessary to perform the cutting operation and this mechanism is herein shown as a rotary disc cutter 12 secured to a shaft 13 which carries a driving pulley 14 adapted to be driven by a belt (not shown) and is rotatably mounted on bearings 15 supported in standards 16 which rise from a horizontal plate 17.

Means are provided to move this cutting mechanism into and out of functioning position and this means is herein shown as an arm 18 which is apertured at 19 to receive a pin 20 secured to the plate 17 and thus rotatably support the cutting mechanism and which is itself carried by a shaft 21 rotatably mounted in a pillar 22 which rises

from a web 23 which in turn is supported by bearings 24 secured to the base plate 25 of the machine frame 26. The shaft 21 and arm 18 are rotated by means of a bevel gear 27 secured to the lower end of the shaft 21 and driven by a cooperating gear 28 secured to the drive shaft 29 which is rotatably mounted in the bearings 24. The pin 20 may be held in position in the arm 18 by means of a nut 36.

In order to further govern the movement of the cutting mechanism and to hold the plane of the cutting disc 12 constantly perpendicular to a given fixed line, in this case the axis of the tube 11, means are provided to govern the rotation of the pin 20 in the aperture 19 and this means is herein shown as a parallel link mechanism consisting of the rods 30 and 31 secured at one end to the plate 17, a disc 32 supported in any suitable manner and secured to the free ends of the rods 30 and 31, and a second pair of rods 33 and 34 secured at one end to the disc 32 and at the other end to a fixed abutment 35.

It will be understood from the above description that rotation of the main shaft 29 acts through the bevel gears 28 and 27 to rotate the vertical shaft 21 and thus cause the arm 18 and the cutting mechanism carried thereby to rotate about the axis of the shaft 21 into and out of functioning position while the parallel link mechanism causes the cutting mechanism to rotate in the arm 18 to hold the plane of the cutting knife continuously perpendicular to the axis of the tube 11.

In order to support the tube and to introduce a shearing element into the cutting operation means are provided to guide and hold the tube at the cutting point during the cutting operation. This means is herein shown as a guide 37 secured to a preferably rectangular rod 38 which is reciprocally mounted in bearings 39 and 40 which are supported by a web 41 rising from the machine frame 26 and braced to the base plate 25 thereof by means of suitable buttresses 42. The guide 37 and rod 38 are biased longitudinally by a spring 43 encircling the forward end of the rod 38 and pressing against the bearing 39 and the enlargement 44 of the rod 38 but such movement of the rod is normally restrained by the engagement of the roller 45 carried by the rod 38

with the arm 46 of a bell crank lever 47 are moving forward at the same speed as which is pivoted at 48 and is provided with a second arm 49 carrying a roller 50 which engages with the periphery of a cam 51. 5 This cam is provided with a depression 52 and is mounted on the drive shaft 29.

Forward movement of the guide 37 and rod 38 under the action of the spring 43 might be governed entirely by the cam 51 10 but in order to secure greater accuracy in the cooperation between the guide 38 and the cutter 12 an arm 53 is projected laterally from the rod 38 and carries a roller 54 arranged to engage the proximate surface 55 15 of the plate 17 when forward movement of the guide 37 is permitted by the cam 51. With such a construction the depression 52 of the cam 51 is made ample to permit the required forward motion and the cooperation 20 between the roller 54 and the edge 55 of the plate 17 is depended upon to exactly govern this forward motion.

The guide 37 may preferably be formed with a funnel shaped entrance portion 56 25 leading into a bore 57 of substantially the size of the tube to be cut. If desired, a second tube guide 58 may be provided to support the tube beyond the cutting plane.

It will be understood from the above description 30 that the cam 51 acting through the bell crank lever 47 normally maintains the rod 38 and guide 37 in the rearward position against the tension of the spring 43 but that when the cam roller 50 rides into the depression 52 the restraint of the rod 38 35 is terminated and the spring 43 acts to move forward the rod and the tube guide carried thereby. The coordination of the parts is, however, such that the edge 55 of the plate 40 17 is now moved into position ahead of the roller 54 carried by the arm 53 of the rod 38 so that the forward movement of the rod is limited by the engagement of the roller 54 with the surface 55 and thereafter the 45 rod moves forward at the same speed as the plate 17 until the cutting operation is completed and the depression in the cam 51 has passed the roller 50 at which time the cam 51 acts through the bell crank lever 47 to 50 move the rod 38 and the guide 37 back into retracted position.

The moving parts of this machine and the connections therebetween are so proportioned 55 that the movement of the cutting mechanism about the axis of the shaft 21 moves the rotary cutting disc across the path of the tube to permit the disc to cut the tube; that the forward movement of the disc in its rotation about the axis of the shaft 21 at 60 the time in which it is cutting the tube is substantially equal to the rate of feed of the tube; that the cam 37 has at this time released the rod 38 so that during the cutting operation the roller 54 is in engagement with 65 the surface 55 and the rod 38 and guide 37

are moving forward at the same speed as the rotary cutting disc and the tube; and that the guide 37 is in such position that the forward end thereof bears against the rear side of the cutting disc 12 to thus introduce 70 the shearing element.

It will be understood that the machine which I have herein shown and described is selected for the purpose of illustration only and the disclosure therein is to be considered 75 as illustrative only and not as in any way limiting my invention to this particular embodiment.

I claim:

1. In a machine for cutting moving material, a pivoted arm having a point thereof moving along the periphery of a circle, a rotary cutting disc pivotally carried by said arm at said point and movable by said arm along said periphery to thereby pass periodically through cutting position at a speed of movement substantially that of the moving material, and parallel link mechanism to maintain the cutting plane of said disc perpendicular to the material to be cut at all 90 times.

2. In a cutting machine for cutting moving material, a movable member having a point thereof moving along a continuous closed path, cutting mechanism connected to said member at said point and movable by said member along said path to thereby pass periodically through cutting position at a speed of movement substantially that of the moving material, and parallel link mechanism to maintain the cutting plane of said cutting mechanism constantly perpendicular to a fixed straight line during the cutting operation.

3. In a machine for cutting moving material, a movable member having a point thereof moving along a continuous closed path, cutting mechanism connected to said member at said point and movable by said member along said path to thereby pass periodically through cutting position at a speed of movement substantially that of the moving material, means to maintain the cutting plane of said mechanism constantly perpendicular to a fixed straight line during the cutting operation, a guide for said material arranged to move relative to said material and to support said material, means tending to move said guide in the direction of movement of said material, means restraining such movement except during the cutting operation, and means cooperating with said cutting mechanism to restrain such movement during the cutting operation to cause said guide to move in the direction of movement of said material at the same speed at which said cutting mechanism moves in said direction.

4. In a machine for cutting moving material, a movable member having a point 130

thereof moving along a continuous closed path, rotary cutting mechanism connected to said member at said point and movable by said member along said path to thereby pass 5 periodically through cutting position at a speed of movement substantially that of the moving material, means to maintain the cutting plane of said mechanism constantly perpendicular to a fixed straight line during 10 the cutting operation, a guide for said material arranged to move relative to said material and to support said material, means tending to move said guide in the direction of movement of said material, a cam restraining such movement except during the cutting operation, and cooperating abutments on said guide and said cutting mechanism to restrain such movement during the cutting operation to cause said guide to 20 move in the direction of movement of said material at the speed at which said cutting mechanism moves in said direction.

5. In a machine for cutting moving material, a movable member having a point thereof of moving along the periphery of a closed conic section, cutting mechanism connected to said member at said point and movable by said member along said path to thereby pass periodically through cutting position 25 at a speed of movement substantially that of the moving material, means to maintain the cutting plane of said mechanism constantly perpendicular to a fixed straight line during the cutting operation, a guide for said material arranged to move relative to said material and to support said material, means tending to move said guide in the direction of movement of said material, a cam restraining such movement except during 30 the cutting operation, and cooperating abutments on said guide and said cutting mechanism to restrain such movement during the cutting operation to cause said guide to move in the direction of movement of said material at the speed at which said cutting mechanism moves in said direction.

6. In a machine for cutting moving material, a movable member having a point thereof moving along a continuous closed path, rotary cutting mechanism connected to said member at said point and movable by said member along said path to thereby pass periodically through cutting position at a speed of movement substantially that of the moving material, means to maintain the cutting plane of said mechanism constantly perpendicular to a fixed straight line during the cutting operation, a guide for said material arranged to move relative to said material and to support said material, and means to move said guide with said material during the cutting operation in such manner that the material to be cut is continuously supported at the point of cutting.

65 7. In a machine for cutting moving ma-

terial, a movable member having a point thereof moving along a continuous closed path, cutting mechanism connected to said member at said point and movable by said member along said path to thereby pass 70 periodically through cutting position at a speed of movement substantially that of the moving material, means to maintain the cutting plane of said mechanism constantly perpendicular to the material to be cut during the cutting operation, a guide for said material arranged to move relative to said material and to support said material, means tending to move said guide in the direction of movement of said material, a cam restraining such movement except during the cutting operation, and cooperating abutments on said guide and said cutting mechanism to restrain such movement during the cutting operation to cause 80 said guide to move in the direction of movement of said material at the speed at which said cutting mechanism moves in said direction.

8. In a machine for cutting moving material, cutting mechanism, means to move said mechanism along a continuous closed path to thus pass said mechanism periodically through cutting position at substantially the speed of said moving material, means to maintain the cutting plane of said mechanism constantly perpendicular to a fixed straight line during the cutting operation, a guide for said material arranged to move relative to said material and to support said material, means tending to move said guide in the direction of movement of said material, means restraining such movement except during the cutting operation, and means cooperating with said cutting mechanism to restrain such movement during the cutting operation to cause said guide to move in the direction of movement of said material at the same speed at which said cutting mechanism moves in said direction.

9. In a machine for cutting moving material, a movable member having a point thereof moving along the periphery of a closed conic section, cutting mechanism connected to said member at said point and movable by said member along said path to thereby pass periodically through cutting position at a speed of movement substantially that of the moving material, means to maintain the cutting plane of said mechanism constantly perpendicular to a fixed straight line during the cutting operation, a guide for said material arranged to move relative to said material and to support said material, and means to move said guide with said material during the cutting operation in such manner that the material to be cut is continuously supported at the point of cutting.

10. In a machine for cutting moving ma-

- terial, a movable member having a point port said material, means tending to move thereof moving along the periphery of a closed conic section, cutting mechanism connected to said member at said point and 5 movable by said member along said path to thereby pass periodically through cutting position at a speed of movement substantially that of the moving material, means to maintain the cutting plane of said 10 mechanism constantly perpendicular to a fixed straight line during the cutting operation, a guide for said material arranged to move relative to said material and to support said material, means tending to move 15 said guide in the direction of movement of said material, means restraining such movement except during the cutting operation, and means cooperating with said cutting mechanism to restrain such movement during the cutting operation to cause said guide to move in the direction of movement of said material at the same speed at which said cutting mechanism moves in said 20 direction.
11. In a machine for cutting moving material, a movable member having a point thereof moving along a continuous closed path, cutting mechanism connected to said member at said point and movable by said member along said path to thereby pass periodically through cutting position at a speed of movement substantially that of the moving material, means to maintain the cutting plane of said mechanism constantly 25 perpendicular to the material to be cut during the cutting operation, a guide for said material arranged to move relative to said material and to support said material, means tending to move said guide in the direction of movement of said material, means restraining such movement except during the cutting operation, and means cooperating with said cutting mechanism to restrain such movement during the cutting operation to cause said guide to move in the direction of movement of said material at the same speed at which said cutting mechanism moves in 30 said direction.
12. In a machine for cutting moving material, cutting mechanism, means to move said mechanism along a continuous closed path to thus pass said mechanism periodically through cutting position at substantially the speed of said moving material, means to maintain the cutting plane of said mechanism constantly perpendicular to a fixed straight line during the cutting operation in such manner that the material to be cut is continuously supported at the point of cutting.
13. In a machine for cutting moving material, a pivoted arm having a point thereof moving along the periphery of a circle, a rotary cutting disc pivotally carried by said arm at said point and movable by said arm along said periphery to thereby pass periodically through cutting position at a speed of movement substantially that of the moving material, parallel link mechanism to maintain the cutting plane of said mechanism constantly perpendicular to a fixed straight line during the cutting operation.
14. In a machine for cutting moving material, a movable member having a point thereof moving along a continuous closed path, cutting mechanism connected to said member at said point and movable by said member along said path to thereby pass periodically through cutting position at a speed of movement substantially that of the moving material; means to maintain the cutting plane of said mechanism constantly perpendicular to the material to be cut during the cutting operation, a guide for said material arranged to move relative to said material and to support said material, means tending to move said guide in the direction of movement of said material, means restraining such movement except during the cutting operation, and means cooperating with said cutting mechanism to restrain such movement during the cutting operation to cause said guide to move in the direction of movement of said material at the same speed at which said cutting mechanism moves in said direction.
15. In a machine for cutting moving material, cutting mechanism, means to move said mechanism along a continuous closed path to thus pass said mechanism periodically through cutting position at substantially the speed of said moving material, means to maintain the cutting plane of said mechanism constantly perpendicular to a fixed straight line during the cutting operation, a guide for said material arranged to move relative to said material and to support said material, and means to move said guide with said material during the cutting operation in such manner that the material to be cut is continuously supported at the point of cutting.
16. In a machine for cutting moving material, a rotary cutting disc, a pivoted member to move said disc along the periphery of a circle to thus pass said disc periodically through cutting position at substantially the speed of said moving material, parallel link mechanism to maintain the cutting plane of said disc perpendicular to the material to be cut at all times, a guide for said material arranged to move relative to said material and to support said material, means tending to move said guide in the direction of movement of said material, a cam restraining such movement except during the cutting

- operation, and cooperating abutments on said guide and said cutting mechanism to restrain such movement during the cutting operation to cause said guide to move in the direction of movement of said material at the speed at which said cutting mechanism moves in said direction. 5
17. In a machine for cutting moving material, cutting mechanism, means to move said mechanism along a continuous closed path to thus pass said mechanism periodically through cutting position at substantially the speed of said moving material, means to maintain the cutting plane of said mechanism constantly perpendicular to a fixed straight line during the cutting operation, a guide for said material arranged to move relative to said material and to support said material, means tending to move said guide in the direction of movement of said material, means restraining such movement except during the cutting operation, and means cooperating with said cutting mechanism to restrain such movement during the cutting operation to cause said guide to move in the direction of movement of said material at the same speed at which said cutting mechanism moves in said direction. 10
18. In a machine for cutting moving material, a movable member having a point thereof moving along a continuous closed path, cutting mechanism connected to said member at said point and movable by said member along said path to thereby pass periodically through cutting position at a speed of movement substantially that of the moving material, means to maintain the cutting plane of said mechanism constantly perpendicular to a fixed straight line during the cutting operation, a guide for said material arranged to move relative to said material and to support said material, means tending to move said guide in the direction of movement of said material, a cam restraining such movement except during the cutting operation, and cooperating abutments on said guide and said cutting mechanism to restrain such movement during the cutting operation to cause said guide to move in the direction of movement of said material at the speed at which said cutting mechanism moves in said direction. 15
19. In a machine for cutting moving material, a movable member having a point thereof moving along a continuous closed path, rotary cutting mechanism connected to said member at said point and movable by said member along said path to thereby pass periodically through cutting position at a speed of movement substantially that of the moving material, means to maintain the cutting plane of said mechanism constantly perpendicular to a fixed straight line during the cutting operation, a guide for said material arranged to move relative to said material and to support said material, means tending to move said guide in the direction of movement of said material, a cam restraining such movement except during the cutting operation, and cooperating abutments on said guide and said cutting mechanism to restrain such movement during the cutting operation to cause said guide to move in the direction of movement of said material at the speed at which said cutting mechanism moves in said direction. 20
20. In a machine for cutting moving material, a movable member having a point thereof moving along a continuous closed path, cutting mechanism connected to said member at said point and movable by said member along said path to thereby pass periodically through cutting position at a speed of movement substantially that of the moving material, means to maintain the cutting plane of said mechanism constantly perpendicular to a fixed straight line during the cutting operation, a guide for said material arranged to move relative to said material and to support said material, means tending to move said guide in the direction of movement of said material, a cam restraining such movement except during the cutting operation, and cooperating abutments on said guide and said cutting mechanism to restrain such movement during the cutting operation to cause said guide to move in the direction of movement of said material at the speed at which said cutting mechanism moves in said direction. 25
21. In a machine for cutting moving material, cutting mechanism, a pivoted arm to move said mechanism along the periphery of a circle to thus pass said mechanism periodically through cutting position at substantially the speed of said moving material, and parallel link mechanism to maintain the cutting plane of said mechanism constantly perpendicular to the material to be cut at all times. 30

In testimony whereof, I have signed my name to this specification this 1st day of June, 1922.

EUGENE CONTI.
